H. M. PFLAGER

ARTICULATED CAR

Filed Dec. 28, 1922

Inventor:
HARRY M. PFLAGER

By *F. R. Connally* *Atty.*

UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

ARTICULATED CAR.

Application filed December 28, 1922. Serial No. 609,523.

To all whom it may concern:

Be it known that I, HARRY M. PFLAGER, a citizen of the United States, residing at St. Louis, Missouri, have invented a certain new and useful Improvement in Articulated Cars, of which the following is a full, clear, and exact description, such as will enable others skilled in the art to which it appertains to make and use the same, reference being had 10 to the accompanying drawings, forming part of this application.

My invention relates to railway rolling stock and consists in an improved platform or underframe construction for use in articulated cars where two adjacent cars have their ends mounted upon a common truck.

The object of my invention is to form integral projections upon the car end sill or buffer member adapted to extend over a 20 truck extending beyond the end of the car and to have center and side bearings removably secured thereto, which bearings may respectively engage the truck center and side bearings.

25 In the accompanying drawings which illustrate a selected embodiment of my invention—

Figure 1 is a top view of the end of a platform casting including my invention.

30 Figure 2 is an end view of the same.

Figure 3 is a longitudinal vertical section through the centers of two adjacent cars and showing the center plate of a common truck upon which the forms are mounted.

35 Figure 4 is a similar section through one of the side bearings.

The casting which is partially shown in Figure 1 is of the usual cast steel type now in use and includes draft sill portions 1, side 40 sill portions 2 and an end sill or buffer portion 3. Cast integrally with the latter portion is a centrally located projection 4 adapted to serve as a platform buffer element or to have attached thereto a body center plate

45 element 5 which is adapted to nest with a similar element 6 secured to the adjacent car. Elements 5 and 6 cooperate to support the two car ends upon a single truck center plate 7.

50 It will be noted that the projection 4 extends downwardly and forwardly and has suitable surfaces 8 facing downwardly and

forwardly which are preferably machined to fit corresponding faces on the center bearing 5.

Spaced from the center of the main platform casting are other integral projections 9 adapted to fit and to have removably attached thereto body side bearings 10 which will be vertically aligned with corresponding truck side bearings.

Both the center bearing and side bearing projections are reinforced by suitable flanges 11 and 12, respectively, and it will be understood that the contour of these projections and the details of their bracing from the buffer or end sill 3 may be varied to suit different conditions and different types of trucks upon which the cars are to be mounted.

With this construction whenever a body bearing is worn or damaged, it may be removed and a new one applied but the essential features of integral supporting structures for the bearings disclosed in my co-pending application Serial Number 609,522, filed Dec. 28, 1922, are retained.

I claim:

1. In a railway car underframe, a member formed integrally upon a permanent 80 part of the underframe, projecting beyond the end of the car, adapted to receive a renewable bearing element adapted to be supported upon a car truck.

2. In a railway car underframe, a projection formed integrally upon the end of the underframe, and a bearing element removably secured to said projection and adapted to be supported upon a car truck.

3. A railway car one-piece underframe casting including an end sill or buffer provided with integral projections at the center of its outer face and at points thereon spaced from the center, and respective body center plate and side plate bearings removably secured to said projections.

4. In a platform casting for a railway car, an integral center projection on the forward end of said casting, and a removable body center plate secured to said projection and provided with a lower surface adapted to be seated on the center plate of a truck extending beyond the end of the car.

5. In a platform casting for a railway car,

integral spaced projections on the forward end of said casting on opposite sides of the center thereof, and removable body side bearings adapted to cooperate with the side bearings of a truck the longitudinal center of which is beyond the front of the platform casting.

6. In a railway car underframe, a member formed integrally upon a permanent part of the underframe, projecting beyond the end of the car, adapted to receive a renewable center bearing element adapted to be supported upon a car truck.

7. In a railway car underframe, a member formed integrally upon a permanent part of the underframe, projecting beyond the

end of the car, adapted to receive a renewable side bearing element adapted to be supported upon a car truck.

8. In a railway car underframe, a member formed integrally upon a permanent part of the underframe, projecting beyond the end of the car, adapted to receive a renewable center bearing element, the last mentioned being adapted on its lower surface to rest upon a complementary bearing of a car truck and on its upper surface to bear against and support a corresponding element on an adjacent car underframe.

In testimony whereof I, hereunto affix my signature this 5th day of Dec., 1922.

H. M. PFLAGER.
